US00D872058S

(12) **United States Design Patent** (10) Patent No.: **US D872,058 S**
(45) Date of Patent: ** Jan. 7, 2020

(54) **REMOTE-CONTROLLER**

(71) Applicant: **Liudong Lai**, Guangdong (CN)

(72) Inventor: **Liudong Lai**, Guangdong (CN)

(**) Term: **15 Years**

(21) Appl. No.: **29/638,794**

(22) Filed: **Mar. 1, 2018**

(51) LOC (12) Cl. **14-03**

(52) U.S. Cl.

USPC **D14/218**

(58) **Field of Classification Search**

(57) **CLAIM**

I claim the ornamental design for a remote-controller, as shown and described.

DESCRIPTION

FIG. 1 is a perspective view of a remote-controller showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
